(57) **CLAIM**

The ornamental design for a package actuator, as shown and described.

DESCRIPTION

FIG. 1 is a rear perspective view of a package actuator of the present invention.

FIG. 2 is a front view of the package actuator depicted in FIG. 1.

FIG. 3 is a left side view of the package actuator depicted in FIG. 1, the right side being a mirror image.

FIG. 4 is a rear view of the package actuator depicted in FIG. 1.

FIG. 5 is a top view of the package actuator depicted in FIG. 1; and,

FIG. 6 is a bottom view of the package actuator depicted in FIG. 1.

The ornamental design which is claimed is shown in solid lines in the drawings.

The dashed broken lines are shown for the purpose of illustrating portions of the package actuator that form no part of the claimed design. The dot-dash broken lines are shown for the purpose of illustrating environmental structure and form no part of the claimed design.
